UNITED STATES PATENT OFFICE.

HUGH H. WILBURN, OF LEWISTON, IDAHO, ASSIGNOR OF ONE-THIRD TO FRED E. BUTLER, OF LEWISTON, IDAHO.

LUBRICATING SYSTEM FOR GAS-ENGINES.

1,125,238.

Specification of Letters Patent.

Patented Jan. 19, 1915.

Application filed December 23, 1912. Serial No. 738,295.

To all whom it may concern:

Be it known that I, HUGH H. WILBURN, citizen of the United States, residing at Lewiston, in the county of Nez Perce and State of Idaho, have invented certain new and useful Improvements in Lubricating Systems for Gas-Engines, of which the following is a specification.

My invention relates to lubricating systems for controlling the supply of lubricating fluid and is particularly adaptable for controlling the depth of oil in the crank case of an engine using the splash system of distribution.

Among the important objects of the invention are to provide arrangement for maintaining a constant level of fluid or oil in the receptacle such as a crank case; to provide arrangement which will enable one controlling mechanism to maintain a constant level of oil in one or more basins or receptacles, as for example crank case sections of an engine; to provide oil level controlling mechanism operated by suction created either by hand operated means or by power driven means; to obtain such suction or vacuum effect by connecting said mechanism directly with the explosion mixture intake pipe or manifold of an engine; to provide controlling mechanism which when applied to an engine will operate independently of the pressure within the crank case, that is, whether the crank case is air-tight or not, and to provide mechanism which will effectively prevent passage of lubricating fluid into the cylinders through the explosion fluid intake connections; and in general to provide simple and efficient controlling mechanism of the character referred to which will primarily deliver lubricating fluid to one or more distributing basins and will then be controlled automatically to maintain the fluid at the proper level.

In the accompanying drawings Figure 1 is a side elevational view of an engine showing the lubricating fluid controlling mechanism applied thereto and showing parts of the engine frame broken away; and Fig. 2 is an enlarged vertical longitudinal sectional view through the fluid reservoir and its associated controlling parts.

In the drawings the engine is indicated in general by the reference character E, the crank casings by the reference character C, and the intake pipe or manifold leading to

the engine cylinders is indicated by the reference character I.

The reservoir 1 for containing the supply of lubricating oil is conveniently mounted in any suitable manner on the engine frame and connected to the bottom wall 2 of the reservoir is the valve casing 3. The oil in the reservoir flows into this casing and its outflow from the casing is through valve opening 4 controlled by the pointed end of needle valve 5 which threads through the stuffing box. The valve outlet 4 may be formed in any manner and as shown is provided in the end of the conducting pipe 8 having a plurality of branches leading to the respective receptacles in which the oil level is to be controlled. The engine shown has two crank case sections and therefore the pipe 8 has the two branches 9 and 10 each leading to one of the sections, the pipe branches preferably communicating with the crank case sections by way of elbow fittings 9' and 10' entering the base of the crank case at the level at which the oil should stand therein for proper operation of the splash distributing system, that is, at the proper level to be engaged and splashed about by the cranks.

The reservoir is filled through opening 11 and closed by a plug or cap 12. Mounted on the top of the reservoir is a hollow frame 13 forming a chamber 13' in which air and oil are separated, the chamber communicating with the reservoir through the nipple 14 extending through the top wall 15 of the reservoir. A hollow neck 16 extends upwardly from the frame 13 and provides at its lower end the conical valve seat 17 with which the ball check valve 18 cooperates. The outflow from the neck 16 is controlled by the cooperation of needle valve 20 with the outlet opening 21. This outlet opening is shown as provided at the end of the pipe 22 extending into the neck and connected at its other end by means of elbow 23 with the manifold I. A removable plug 24 is provided for the upper end of the neck.

The operation of the system can now be understood. When starting a new engine or when applying fresh oil, the outlet opening 4 is closed by valve 5 and the plug 12 withdrawn and the reservoir filled with oil. After such filling, the plug is replaced and the valve 5 is opened so that the oil may run through outlet 4 and through conducting 110

pipe sections 9 and 10 to the respective crank cases. As the ball valve 18 is held by gravity against its seat and thus prevents inlet of air to replace oil flowing out of the reservoir, 5 air must flow upwardly through the conducting pipes 9 and 10 and into the reservoir and as soon as the outlets of pipes 9 and 10 are closed further flow of air will be prevented. When the crank case sections are 10 empty, the ends of pipe sections 9 and 10 are of course fully open to the interior of the crank case sections and air will flow upwardly through the pipes and into the reservoir to replace the oil flowing down through 15 the pipes into the crank chambers, the oil flowing along the bottoms of the pipes and the air flowing along the tops thereof. The arrangement is such that as soon as the oil in the crank case sections reaches the level proper for efficient 20 operation of the splash distributing system, the outlets of the conducting pipes are closed and thus further flow of oil from the reservoir into the crank case sections will be prevented, as the reservoir is then air-tight. 25 The engine is now started and the suction caused in the manifold I by the descending pistons is communicated through pipe 22 to the neck and valve chamber therein, and the ball check 18 is raised so that air is withdrawn 30 from the separator compartment 13' and from above the oil in the reservoir. This suction or vacuum effect will eventually raise the oil in the reservoir so that oil is drawn up from the crank case sections into 35 the reservoir. However, immediately that the oil in the crank case sections lowers sufficiently to expose the outlet ends of the conducting pipes, air instead of oil will flow up the conducting pipes and into the reservoir and oil will flow down the pipes to again 40 raise the oil in the crank case sections until the conducting pipe outlets are again sealed. Thus the engine intake suction is effective in 45 the reservoir and tends to raise the oil therein, while oil will immediately tend to flow out of the reservoir back into the crank case sections as soon as the oil in the crank case sections lowers sufficiently to unseal the conducting pipe ends. Thus the oil in the crank 50 case sections is maintained at substantially constant level. When the engine stops, the suction effect on the reservoir also stops but the check valve 18 will immediately close 55 and the reservoir will be entirely sealed against air. Should at any time the oil accidentally flow out of the reservoir into the crank case sections it will immediately be drawn back into the reservoir and reduced 60 to the proper level in the crank case when the engine is operated either manually or by power. In the chamber 13' the oil and air are separated, the oil flowing back into the reservoir and the air passing upwardly past 65 the valve 18 and through pipe 22 into the

cylinders when the engine is operating. The suction effect is, however, so controlled that it will never be sufficient to draw oil any distance up into the chamber 13'. Such control may be effected by adjusting the size of 70 outlet 21 by means of needle valve 20; or pipe 22 could be of sufficiently small bore to properly reduce the suction effect. Thus it is impossible for any oil to reach the manifold I or the cylinders, and the quality of 75 the explosion mixture which may enter the cylinders through the manifold will not in any way be interfered with.

I do not of course desire to be limited to the precise construction and arrangement 80 shown and described as modified constructions and arrangements could be made which would still fall within the scope of the invention and

I claim the following:

1. In a lubricating system, the combination of a reservoir for lubricating fluid, a conductor pipe leading from said reservoir below the oil level therein and to a receptacle to be supplied with fluid, means for reducing below atmospheric pressure the pressure in said reservoir above the fluid, and means for sealing the reservoir above the fluid when said pressure reducing means ceases to operate.

2. In a lubricating system, the combination of a reservoir for lubricating fluid, a conductor pipe leading from said reservoir below the oil level therein and to a receptacle to be supplied with fluid, means for reducing below atmospheric pressure the pressure in said reservoir above the fluid, and a check valve for sealing the reservoir above the fluid against air inflow upon cessation of operation of the pressure reducing means.

3. In combination, a receptacle to be supplied with fluid, a fluid reservoir above the normal level of fluid in said receptacle, a conductor pipe extending from said reservoir below the fluid level therein and to said receptacle with its outlet at the normal level of the fluid in the receptacle whereby when said fluid level falls said outlet will be exposed to air flow, means for reducing below 110 atmospheric pressure the pressure in said reservoir above the fluid therein whereby fluid will be drawn from the receptacle into the reservoir until fluid in the receptacle falls to unseal the outlet of the conducting pipe, and means for sealing the reservoir above the fluid against air inlet upon cessation of operation of the pressure reducing means.

4. In a fluid controlling system, the combination of a plurality of receptacles to be supplied with fluid, a fluid reservoir above the normal level of fluid in said receptacles, a conductor pipe leading from said reservoir to each of said receptacles with its outlet 125

130

terminating at about the normal level plane for fluid in the receptacles, pressure reducing mechanism associated with the reservoir above the fluid level therein, and means for sealing the reservoir above the fluid therein against the inlet of air upon cessation of operation of the pressure reducing mechanism.

5. In a lubricating system for explosive engines, the combination of a lubricating fluid reservoir, a conducting pipe leading from said reservoir below the level of the fluid therein and to the engine crank case with its outlet at substantially the level in which fluid should stand in the crank case for proper lubrication, piping leading from the reservoir above the fluid therein to the intake end of the engine cylinder whereby upon operation of the engine the suction will effect reduction of pressure in the reservoir, 20 and a check valve for sealing the reservoir against air inflow when the engine is at rest.

6. In a lubricating system for explosive engines, the combination of a fluid reservoir, a conducting pipe leading from said reservoir below the level of fluid therein and terminating in the engine crank case at substantially the level at which fluid should stand in the crank case for effective lubrication, piping connecting the reservoir above the fluid therein with the intake end of the engine cylinder whereby suction created upon operation of the engine will be transmitted to the reservoir and the pressure reduced therein, means for reducing the suction effect, and means for sealing the reservoir above the fluid therein when said engine ceases to operate.

7. In a lubricating system for explosive engines, the combination with the engine cylinder and crank case, of a lubricating fluid reservoir, a supply pipe leading from said reservoir below the level of fluid therein and into the crank case, suction piping leading from the reservoir above the fluid level and connecting with the intake end of the cylinder, and a separating chamber interposed between the suction pipe and the reservoir.

8. In a lubricating system, the combination of a reservoir for lubricating fluid, a conductor pipe leading from said reservoir below the fluid level therein to a receptacle to be supplied with fluid, means for reducing below atmospheric pressure the pres-

sure in said reservoir above the fluid where- 55 by fluid will be drawn into the reservoir from the receptacle, and means for preventing return flow of fluid to the receptacle when said pressure reducing means cease to operate.

9. In a lubricating system for explosive engines, the combination of a lubricating fluid reservoir, a conducting pipe leading from said reservoir below the level of the fluid therein to the engine crank case with 65 its outlet at substantially the level in which fluid should stand in the crank case for proper lubrication, piping leading from the reservoir above the fluid therein to the intake end of the engine cylinder whereby 70 upon operation of the engine the suction will effect reduction of pressure in the reservoir and flow of fluid from the crank case to the reservoir, and means for preventing return flow of fluid to the crank case when the 75 engine ceases to operate.

10. In a lubricating system for explosive engines, the combination of a lubricating fluid reservoir, a conducting pipe leading from said reservoir to a receptacle to be supplied with fluid, piping leading from the reservoir above the fluid therein to the intake end of the engine cylinder whereby upon operation of the engine the suction will effect reduction of pressure in the reservoir 80 and will tend to draw fluid from the receptacle into the reservoir, a restricted passageway in said piping for preventing flow of fluid from the reservoir to the cylinder, and means for adjusting the size of said 85 restricted passageway.

11. In a lubricating system, the combination of lubricant chambers, one of said chambers having its lubricant level above the plane of the lubricant level of the other 95 chamber, means for reducing the pressure in the upper chamber to less than atmospheric pressure, and means for preventing the ingress of air to said upper chamber except when the lubricant in the lower chamber is 100 below the desired level of the lower chamber.

In testimony whereof I affix my signature in presence of two witnesses.
